MUTE FOR VIOLINS

Harry L. Van Ham, West Roxbury, Mass.

Application April 25, 1939, Serial No. 270,001

2 Claims. (Cl. 84—311)

The invention relates to a sound control attachment for string musical instruments and more particularly to a mute for a violin.

The primary object of the invention is the provision of a mute of this character, wherein the same can be worn on the strings of a violin or the like and is susceptible of being moved for varying the tone or sound qualities of the strings required in the playing of music, the mute being novel in its make-up and in the attachment thereto of the instrument.

Another object of the invention is the provision of a mute of this character, wherein the same is attached between the tail piece and the bridge of the musical instrument, particularly a violin, viola or cello and is susceptible of hand manipulation for tone variation in the playing of the strings of the instrument.

A further object of the invention is the provision of a mute of this character, which is extremely simple in its construction, thoroughly reliable and efficient in operation, readily and easily applied to and removed from a musical instrument of the string type, being possessed of few parts yet strong, durable, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary perspective view of a violin showing the mute constructed in accordance with the invention attached.

Figure 2 is a fragmentary side elevation.

Figure 3 is a view similar to Figure 2 showing the mute in an adjusted position.

Figure 4 is a sectional view on the line 4—4 of Figure 3.

Figure 5 is an enlarged vertical transverse sectional view through the mute.

Similar reference characters indicate corresponding parts throughout the several views in the drawing.

Referring to the drawing in detail, A designates generally a portion of a string musical instrument exemplified as a violin and includes as is customary a tail piece 10, bridge 11 and strings 12, respectively, these being adjustable and played in the usual manner. Adapted to be attached to the strings 12 between the tail piece 10 and the bridge 11 is a mute constituting the present invention and hereinafter fully described.

The mute comprises block-like lower and upper sections 13 and 14, respectively, these being joined superposed relative to each other in matched relation by a screw 15, which is passed

through the upper section 14 and threaded into the lower section 13. The sections 13 and 14 at their faces next to each other in the connected manner by the screw 15 carry felt pieces 16, the strings 12 being trained between the said sections and the pieces 16 having contact therewith. The mute including the sections 13 and 14 is adjustable toward and away from the bridge 11 for sound control purposes.

The section 13 is formed with a beveled face 17 next to the bridge 11 and this face wears a felt covering 18 adapted for contact with the bridge when the mute has been adjusted in close relation thereto. The mute when contacting with the bridge deadens the sound of selected strings of the musical instrument for muting purposes while on movement of the mute in the direction of the tail piece 10 the natural tone qualities of the strings affected by said mute are returned to normalcy, giving forth natural tone or sound qualities. The mute is hand adjustable and is to be permanently worn by the musical instrument in the manner as hereinbefore stated.

The mute including the sections 13 and 14 can be made from wood, Bakelite or any other material. It is preferable to have the pieces 16 made from leather and are adhesively joined to the said sections while the covering 18 is preferably made from felt or the like.

What is claimed is:

1. A mute for a stringed musical instrument having a tail piece and bridge for the strings thereof, comprising a narrow sectional body entirely free of the tail piece and bridge and wholly suspended by selected strings on engagement between the sections of said body, cushioning pieces permanently fastened to the sections of the body at confronting faces thereof for contact with the selected strings, and a second pad permanently carried at one side face of one section of the body for making contact with the bridge of the instrument.

2. A mute for a stringed musical instrument having a tail piece and bridge for the strings thereof, comprising a narrow sectional body entirely free of the tail piece and bridge and wholly suspended by selected strings on engagement between the sections of said body, cushioning pieces permanently fastened to the sections of the body at confronting faces thereof for contact with the selected strings, a second pad permanently carried at one side face of one section of the body for making contact with the bridge of the instrument, and a fastener engaging the sections of the body for adjustably connecting these sections together and the frictional clamping of selected strings between said sections.
